(57) **CLAIM**

The ornamental design for a pod mountable to an aircraft, as shown and described.

DESCRIPTION

FIG. 1 is a top perspective view of a pod mountable to an aircraft showing my new design;

FIG. 2 is a bottom perspective view of the pod mountable to an aircraft shown in FIG. 1;

FIG. 3 is a left side view of the pod mountable to an aircraft shown in FIG. 1;

FIG. 4 is a front view of the pod mountable to an aircraft as shown in FIG. 1;

FIG. 5 is a rear view of the pod mountable to an aircraft shown in FIG. 1;

FIG. 6 is a top view of the pod mountable to an aircraft shown in FIG. 1;

FIG. 7 is a bottom view of the pod mountable to an aircraft shown in FIG. 1; and,

FIG. 8 is a right side view of the pod mountable to an aircraft shown in FIG. 1.
